(57) **CLAIM**

The ornamental design for a hand-held controller for virtual-reality system, as shown and described.

DESCRIPTION

FIG. 1 is a top, left perspective view of a hand-held controller for virtual reality system showing our new design; FIG. 2 is a top, right perspective view thereof; FIG. 3 is a top, right-rear perspective view thereof; FIG. 4 is a top plan view thereof; FIG. 5 is a left side elevational view thereof; FIG. 6 is a right side elevational view thereof; FIG. 7 is a right-rear elevational view thereof; FIG. 8 is a left-rear elevational view thereof; FIG. 9 is a rear elevational view thereof; FIG. 10 is a bottom-right perspective view thereof; and, FIG. 11 is a bottom view of the design of FIGS. 1–10. The broken lines indicate unclaimed portions and form no part of the claimed design. The claimed design discloses a left hand use of the article and it is understood that the right hand use of the article is the mirror image of the disclosed claimed design.
